REFRIGERATOR

Walter A. Kuenzli, Evansville, Ind., assignor to
Servel, Inc., New York, N. Y., a corporation of
Delaware

Application April 12, 1937, Serial No. 136,256

3 Claims. (Cl. 20—35)

My invention relates to refrigerators, and more particularly to refrigerator door structure.

It is an object of the invention to provide an improved refrigerator door structure in which a minimum number of parts are employed and in which the assembly of the door is facilitated considerably. I accomplish this by providing corner brackets for the inner and outer wall members of a door, the corner brackets being secured to both the inner and outer wall members and constituting the frame structure for the door. The corner brackets are preferably arranged to serve as sections or parts of a breaker strip extending about the periphery of the door.

The invention, together with the objects and advantages thereof, will be more fully understood from the following description taken in conjunction with the accompanying drawing forming a part of this specification, and of which Fig. 1 is a front elevation of a refrigerator provided with a door embodying the invention; Fig. 2 is an enlarged rear elevation, partly broken away, of the door illustrated in Fig. 1; Fig. 3 is an enlarged fragmentary view, partly broken away and in section, of a corner of the door shown in Figs. 1 and 2; Figs. 4 and 5 are fragmentary sectional views taken at lines 4—4 and 5—5, respectively, of Fig. 3; Fig. 6 is a sectional view similar to Fig. 4 illustrating a modification of the invention; and Fig. 7 is a perspective view of a part shown in Fig. 6.

Referring to Fig. 1, I have shown a refrigerator comprising a cabinet 10 having a thermally insulated storage space 11 into which access may be had by a door 12 hinged to the front of the cabinet. Within the storage space 11 is arranged a cooling element 14 for producing cold and maintaining space 11 at a desired low temperature.

The door 12 includes inner and outer wall members 15 and 16 having the space therebetween filled with a suitable heat insulating material 17. The inner wall member 15 is provided with an inclined flange 18 which extends toward the outer wall member 16. The outer wall member 16 extends beyond the inner wall member 15 and is bent back upon itself to form a ledge 19 which overlies the front exterior wall of the cabinet 10 when the door is in its closed position. The extreme peripheral edge portion 20 of the outer wall member 16 is inclined to the ledge 19 and extends toward the inner wall member 15.

A multi-section gasket is provided at the ledge 19 for effectively sealing the door 12 when it is locked in its closed position. The gasket includes

corner pieces 21 located at the corners of the door and straight pieces 22 extending between the corner pieces 21. The corner and straight pieces 21 and 22 of the gasket are formed of a suitable resilient material, such as rubber, for example, the corner pieces 21 preferably being molded into the desired shape with a radius of curvature which conforms to the curved or rounded corners of the door.

As shown most clearly in Fig. 4, the corner pieces 21 are formed with an intermediate flat portion 23 having a hollow striking bead 24 at the curved outer edge thereof, and an inner edge portion 25 which is at an angle and inclined to the flat portion 23. The flat portion 23 and striking bead 24 bear against the inside of ledge 19, and the inclined portion 25 bears against the inclined flange 20 of the outer wall member 16.

The straight pieces 22 of the gasket, which may be formed of extruded rubber, are similar in cross-section to the molded corner pieces 21 and are provided with a flat portion 26 having a hollow striking bead 27 at the outer edge thereof. In order that the striking beads 24 and 27 will in effect form a continuous striking bead about the ledge 19, the corner pieces 21 are provided with tongues 28 which are semi-circular in shape and extend beyond the ends of the striking beads 24. The tongues 28 extend and fit into the hollow ends of the striking beads 27, as shown in Fig. 3, whereby the striking beads 24 and 27 are effectively joined and connected together. The corner pieces 21 and straight pieces 22 preferably are of such length that the force applied to the striking bead when the door is closed will effectively seal the joints between the separate pieces of the gasket.

The straight pieces of the gasket form part of a combined gasket 22 and breaker strip 29, the latter being integral with and at an angle to the flat portion 26 and extending toward the inner wall member 15. The breaker strip 29 is provided with lips 30 to provide grooves which receive the edges of the flanges 18 and 20 of the inner and outer wall members 15 and 16. The outer edge of the breaker strip 29 bears against the flange 20 and the inner edge thereof bears against the flange 18. The breaker strip portion 29 of the combined gasket and breaker strip may be formed of harder rubber than the gasket portion 22, particularly the striking bead 27 which is preferably formed of soft rubber. The combined gasket and breaker strip is so formed and shaped that the space between the flanges 18

and 20 is effectively sealed with the flanges snugly fitting into the grooves formed by the lips 30.

In accordance with my invention, the inner and outer wall members 15 and 16 are maintained in spaced relation by four corner brackets 31 which serve as a frame structure for the door. The brackets 31, which may be formed of metal or other suitable material, are curved or rounded to conform to the rounded corners of the door and include an inclined portion 32 and a flange 33. The inner edge of the inclined portion 32 is secured by screws 34 to the flange 18 of the inner wall member 15. The flange 33 is also secured by screws 35 to the inside of the ledge 19. By interposing the flat and inclined portions 23 and 25 of the corner pieces 21 between the brackets 31 and the outer wall member 16, the inner and outer wall members are effectively insulated from each other.

In addition to serving as a frame structure for the door, the corner brackets 31 are also utilized as sections or parts of the breaker strip about the periphery of the door. The brackets 31 connect or join the strips 29 at the sides of the door and slightly overlap the ends of the latter, as indicated at 36 in Fig. 3, whereby the entire periphery of the door is effectively sealed.

It will now be understood that an improved door structure has been provided in which a minimum number of parts are employed and which is easily assembled. After the inner and outer wall members 15 and 16 are blanked with openings at the corners of the flange 18 and ledge 19, as indicated at 37 and 38, respectively, the insulating material is placed in position against the inside of the outer wall member 16. The corner pieces 21 and combined gasket 22 and breaker strips 29 are then placed about the ledge 19 with the flange 20 snugly fitting into the outer groove of the breaker strips 29. The corner pieces 21 are positioned at the corners of the ledge 19 so that the openings in the corner pieces and in the ledge are in alignment. The flange 33 of the corner brackets 31 are then secured to the ledge 19 by the screws 35. With the brackets 31 secured to the outer wall member 16, the inner wall member 15 is placed in position so that the flange 18 snugly fits into the inner groove of the breaker strips 29. The brackets 31 are next secured to the flange 18 by the screws 34 to complete the assembly of the door structure.

In order to avoid cracking of the porcelain enamel at the corners of the inner wall member 15 when the brackets 31 are secured thereto by the screws 34, the door structure just described may be modified in the manner shown in Fig. 6. In the modification the flange 18 of the inner wall member 15 is provided with a plurality of spaced openings at the door corners, only one of which is shown in Fig. 6. Before the inner wall member is porcelain enameled, or finished in any other suitable manner, a speed nut 39 is secured in place at each of the openings by bending over the tabs 40. When the brackets 31 are secured to the inner wall member 15, the screws 41 are tightened up on the speed nuts 39. In this manner any likelihood of cracking the porcelain enamel of the inner wall member 15 is completely avoided.

While several embodiments of my improved refrigerator door structure have been shown and

described, such variations and modifications are contemplated as fall within the true spirit and scope of the invention, as pointed out in the following claims.

5. What is claimed is:

1. Refrigerator cabinet structure including a door and having spaced apart wall members, one of said wall members having openings adjacent the edge portions thereof, brackets for maintaining said members in spaced relation, attaching means for securing said brackets to said wall members comprising means for removably attaching one side of said brackets to one of said wall members and a second attaching means for removably securing the other side of said brackets to the other of said wall members, said second attaching means comprising a pair of cooperating elements one of which is removably secured to said wall member within said openings and positioned to underlie said brackets, and means connecting said element to the overlying portions of said brackets and adapted to space said overlying portions from said elements at a distance sufficient to enable the other of said cooperating elements to take up all the play and draw said brackets and said one wall member tightly together.

2. In a refrigerator door having spaced apart wall members, one of said wall members having openings at the corners thereof, nuts removably secured in said openings, brackets at the corners of said door constituting the frame structure for maintaining said members in spaced relationship, screws cooperating with said nuts for securing said bracket to said one wall member, means for attaching said brackets to said wall members, said attaching means comprising removable means for securing one side of said bracket to one of said members, and means, in the region of said openings, on said other wall member and adjacent to and underlying the other side of said bracket and coacting with means on said bracket for maintaining said wall member and said bracket in spaced relation whereby the overlying portions of said brackets are spaced from said nuts to ensure tightly securing said brackets to one of said wall members when said screws are drawn on said nuts.

3. Refrigerator cabinet structure including a door and having spaced apart wall members, one of said wall members having openings adjacent the edge portions thereof, brackets for maintaining said members in spaced relation, attaching means for securing said brackets to said wall members comprising means for removably attaching one side of said brackets to one of said wall members and a second attaching means for removably securing the other side of said brackets to the other of said wall members, said second attaching means comprising a pair of cooperating elements one of which is removably secured to said wall member within said openings and positioned to underlie said brackets, and means connecting said element to the overlying portions of said brackets and adapted to coact with means on said bracket to space said overlying portions from said elements at a distance sufficient to enable the other of said cooperating elements to take up all the play and draw said brackets and said one wall member tightly together.

WALTER A. KUENZLI.
